STRAIGHT BAR KNITTING MACHINE

Kurt Willi Wickardt, Liverpool, England, assignor to Hosemaster Machine Company Limited, Liverpool, England, a British company

Application March 24, 1951, Serial No. 217,353

Claims priority, application Great Britain March 27, 1950

14 Claims. (Cl. 66—82)

1

The present invention relates to straight bar knitting machines, and is especially, although not exclusively, applicable to straight bar knitting machines for knitting full fashioned hosiery.

Such machines embody a row of needles and other loop-forming elements to form a knitted fabric, and cams are provided to control the motions of these various elements.

It is necessary for certain of these cams for example the draw cams to be taken out of operation and then to be put into operation again, i. e. to be rendered stationary for certain intervals of time whilst the machine continues to run i. e. it is necessary for such cams to be intermittently operated. This involves the use of clutching means for driving the cams from a source of power, usually from a main cam shaft. The clutching means are usually of the dog-clutch type, that is to say they are of the type in which the cam or the like is almost immediately brought up to the speed of its driving means as the clutch is brought into engagement. Clutching means of this type, as distinct from friction clutches or other gradually applied clutches, have been used by reason of the necessity for accurate phase relationship between each cam and its driving means so as to preserve the timing between the various parts of the whole machine. Thus, a good deal of shock has been necessarily involved in the engagement of these cams with their driving means.

The present invention consists in a nonfrictional clutching device for such intermittently operated cams or other intermittently rotatable parts of a straight bar knitting machine, which will achieve a more gradual acceleration of the cam or other part whilst preserving its phase relationship with its driving means. More particularly, in a straight-bar knitting machine including at least one intermittently operated element such as an intermittently operated cam driven in a given direction, the present invention consists in the provision of a clutching device adapted to afford a gradual but positive acceleration of said intermittently operated element in said given direction to bring it into a given phase relationship with its driving means, said clutching device including a driving member and a driven member, which latter may be said intermittently operated element, one of said members having an abutment, such as a groove or rib, of gradually changing direction including a portion directed substantially at right angles to said given direction whilst the other of said members has a withdrawable element adapted to engage said abutment, means being provided for bringing said withdrawable element and said abutment into engagement by producing a condition of relative motion therebetween which motion includes a component in said given direction.

2

Means may similarly be provided for achieving a gradual disconnection between the driving and driven members. Thus, oppositely curved and intermerging grooves or ribs on one of the members

5 may be adapted for engagement by a single withdrawable element, such for example as a pin, which can be transferred from one groove, after engagement of the clutch, to the other under the control of a suitable latch or detent mechanism adapted to prevent the slideable element from retracing its path along the first groove or rib. Alternatively, one of the members may have two separate oppositely curved grooves or ribs adapted for engagement with two withdrawable elements, 10 one of which is engageable with one of the grooves or ribs to achieve a clutching of the driven member to the driving member, whereupon the other withdrawable element is engaged with the other groove or rib and the first withdrawable element

15 disengaged.

In a particular form of construction, for example, a rotatable cam or like driven member may have a cylindrical outer surface with oppositely curved grooves formed in its cylindrical

20 surface from one edge thereof, these cam grooves at their open ends being spaced apart by a distance greater than their spacing at their closed ends. The driving member, such for example as a shaft, may be provided with a spider bearing 25 two spaced radially directed clutching pins adapted to be moved endwise, i. e. in a radial direction, for respective engagement with and withdrawal from said grooves of the driven member.

30 35 For engagement and disengagement of the pins with the cam grooves, means may be provided for collectively moving them in the axial direction of the cam and for individually moving them in the radial direction. Their axial movement may be 40 achieved by axial movement of the spider on which they are mounted.

Movements of said pins in the radial direction 45 may be controlled by profile elements located in their path of travel and engaging with projections on the pins extending in the axial direction of the cam. One such profile element may be

provided in the path of travel of the pins for inwardly displacing one of the pins to bring it 50 into a position for engagement with one of the grooves in the cam, whilst a second profile element may thereafter withdraw the other pin after it has brought the cam into motion at equal speed with its driving means. A second set of profile elements may be provided for withdrawing the 55 first-mentioned pin and inwardly displacing the second pin into a position for engagement with one of the grooves in the cam or drive element after the first pin has decelerated the cam or drive element and been disengaged therefrom.

60 The present invention is especially useful for

the starting and stopping of the rotary cam which controls the slur cock which actuates the sinkers.

The invention will be further described with reference to the accompanying drawings which show, by way of example embodiments of the invention as applied to a Cotton's patent straight bar knitting machine.

In the drawings:

Fig. 1 is a diagrammatic plan view of one embodiment of the invention,

Fig. 2 is a back elevation of Fig. 1,

Fig. 3 is a diagrammatic detail to an enlarged scale showing the paths of movement of the driving member in space and relative to the driven member before, during, and after engagement and disengagement,

Fig. 4 is a diagrammatic detail to an enlarged scale showing one stage during the engagement of the clutch,

Fig. 5 is a detail view to an enlarged scale in section taken along the line V—V of Fig. 4,

Fig. 6 is a plan view of a second embodiment of the invention,

Fig. 7 is a diagrammatic end sectional view of Fig. 6 to enlarged scale with certain parts removed,

Fig. 8 is a plan view to an enlarged scale corresponding to Fig. 7,

Fig. 9 is a diagrammatic detail to an enlarged scale showing the paths of the driving member in space and relative to the driven member before, during and after engagement and disengagement, and

Fig. 10 is a diagrammatic plan view of a third embodiment of the invention.

In the drawings there has only been shown sufficient detail of the parts of the knitting machine as will enable the present invention to be understood and other parts which will be well known to those skilled in the art have been omitted for the sake of clarity.

In the drawing like parts are indicated by like reference numerals. Driving shaft 11 carried in bearings in frame members 12 and 12' carries driven member 13 loosely between collars 14, 15. Driving member 16 is slidably carried on shaft 11 and keyed to rotate therewith by means of key 17, and carries one or more extensions 18, 18' each carrying a pin 19 or two complementary pins 20, 21 which are adapted to engage with grooves 36, 37 formed in the driven member 13 as will be hereinafter described. Axial movement of the driving member 16 to bring it into engagement with the driven member is effected by means of axial cam 22 and radially displaceable cam roller 23 when in its inner position, as indicated by 23', and reverse movement of driving member 16 to bring it out of engagement with the driven member by means of oppositely directed axial cam 24 and roller 23 when in its outer position. The roller 23 is carried at one end of a pin 26 connected to a plate 27 carrying a follower 28 co-operating with a radial cam 29 on the shaft 11, and also carrying a further pin 30, both pins 26 and 30 passing through a fixed support 33. The plate is resiliently urged towards the support by spring 32. A detent 34 movable into and out of the space between the plate 27 and the support 33 by means of rod 35 in a manner known per se prevents or permits movement of the plate 27. When the detent 34 is moved out of the space the plate 27, and hence the roller 23, is moved inwardly towards the shaft 11 under the control of the radial cam 29, thus moving the roller

23 out of the region of engagement with one axial cam 24 and into the region of the other axial cam 22 to bring about axial movement of the driving member 16.

Two grooves 36, 37 are provided on the driven member 13 for the engagement and disengagement of the pin 19 or pins 20, 21 which extend radially inwardly from the extension 18 on the driving member 16. The curved grooves extend generally axially of the driven member 13 and have outer portions 36', 37' at the end of the hub inclined to the axis of the hub, and inner end portion parallel to the axis of the hub, i. e. at right angles to the direction of rotation of the hub. The outer portion of each groove is preferably at such an angle to the axis of the driven member that it corresponds with the direction of movement of the radially inwardly extending roller or pin on the driving member at the instant of its first coming into contact with or going out of contact with the driven member. Thus in engagement a pin may engage the hub with a minimum of shock and further axial movement of a pin after initial engagement causes the pin to travel down the groove until it reaches the inner end of the groove which extends axially of the driven member, thus accelerating the driven member until both driven and driving members are rotating at the same speed.

The two grooves 36, 37 are complementary to one another, i. e. they are oppositely curved, the pin moving inwardly along one groove 36 during engagement and outwardly along the other 37 during disengagement.

The two grooves 36 and 37 may merge at their inner ends as shown particularly in the embodiment illustrated in Figs. 1 to 5 of the accompanying drawings, thereby enabling a single pin 19 to be used, or may be separated from one another as shown particularly in the embodiment illustrated in Figs. 6 to 9 thereby requiring the use of two pins 20, 21 in succession.

The embodiment shown in Figs. 1 to 5 will now be described in greater detail. The two grooves 36 and 37 merge at their inner ends i. e. at the axial portion, as is shown in Fig. 2 and more clearly in Figs. 3 and 4. The two grooves, are, however, separated adjacent their axial portion by a small rotatable insert in the form of a circular disc inserted in a transverse opening in the driven member so that it will be rotatable about a radial axis and having an upstanding more or less triangular shaped tongue 39 one apex of which adjoins the junction of the adjacent walls of the two grooves 36, 37 so that it is adapted, by rotation, to open one groove and close the other. The insert is resiliently urged by spring 40 into the position shown diagrammatically in Fig. 3 so as normally to open groove 37.

The paths of movement of the pin 19 in space and relatively to the driven member 13 before, during and after engagement are indicated diagrammatically in Fig. 3 which is a developed view of the driven member. Prior to engagement the pin 19 travels along the path indicated by the chain dotted line 41 and during engagement the driving member is moved axially by means of cam 22 and roller 23, so that the pin 19 is caused to travel along the path indicated by full arrows 42 and after engagement the pin will travel along the path indicated by chain dotted line 43. During engagement the pin 19 will enter the leading portion 36' of groove 36, move along groove 36, and contact one side of insert tongue 39 causing it to rotate in an anticlockwise direction to

open groove 36 and permit the pin to move into the inner axial end of the groove 36. The path of movement of the pin 19 relatively to the driven member 13 during engagement is indicated in Fig. 3 by the dotted arrows 44. The displaced position of the insert 38 and tongue 39 and the path of the pin are indicated diagrammatically in Fig. 4, which is also a diagrammatic developed view of the driven member, and in Fig. 5.

After passage of the pin 19 the insert 38 is returned to its normal position by spring 40 to close the first passage 36 and open the second passage 37 in preparation for the movement of the pin therealong during disengagement.

The paths of movement of the pin 19 in space and relatively to the driven member 13 before, during, and after disengagement are indicated diagrammatically in Fig. 3. Prior to disengagement the pin 19 travels along the path indicated by the chain dotted line 43 and during disengagement the driving member is moved axially, in the opposite direction to that during engagement, by axial cam 24 and roller 23, so that the pin 19 is caused to travel along the path indicated by the open arrows 45, and after disengagement the pin will travel once more along the path indicated by the chain dotted line 41. The path of movement of the pin 19 from its engaged position 19', and along groove 37 relatively to the driven member 13 during disengagement is indicated in Fig. 3 by the chain dotted arrows 46.

It will be understood that the purpose of the insert 38 and tongue 39 is to ensure that the pin 19 travels along groove 37, and not along groove 36, during disengagement.

In another embodiment shown in Figs. 6, 7, 8 and 9 the driven member 13 provided with two separate circumferentially spaced grooves 36, 37 and two circumferentially spaced pins 20, 21 are provided on the driving member 16 each to engage one of the grooves. It is, however, necessary that for engagement one pin 20 must be moved inwardly radially into a position to engage one groove 36 while the other pin 21 is moved outwardly into a position to clear the outer face of the driven member 13.

For this reason oppositely directed axially extending projections 47 and 48 are provided adjacent the outer ends of pins 20, 21 respectively which are radially slideable in extension 18 of the driving member and means such as detent pins 49, 50 and compression spring 51 co-operating with notches 52 formed in the pins 20 and 21 are provided for locating each pin in either an inner position, for engagement with a groove in the driven member, or in an outer position for non-engagement with a groove. Additionally two sets of cam surfaces 53, 54 and 55, 56 on brackets 57, 58 attached to the machine framework, are provided to contact the projection on the pins, the one set being operative when the driving member is in the disengaged position, and the other set when the driving member is in the engaged position. The cam surfaces are in fixed angular relationship with one another and are axially spaced apart so that one cam surface in each set contacts the projection on one pin and the other cam surface in the set partly concurrently and partly subsequently contacts the projection on the other pin. Thus cam surfaces 53 and 56 co-operate with projection 47 on pin 20 in the disengaged and engaged positions of the driving member respectively, and cam surfaces 54 and 55 co-operate similarly with projection 48 on pin 21.

The sequence of operations during engagement

and disengagement will now be described. The paths of movement of the pins 20, 21 in space and relatively to the driven member before, during and after engagement are indicated diagrammatically in Fig. 9 which is a developed view of the driven member. Prior to engagement, pin 20 is in its inner position and pin 21 in its outer position, and they travel along the path indicated by the chain dotted line 41 and during engagement the driving member 16 is moved axially by means of cam 22 and roller 23 so that pin 20 is caused to travel along the path indicated by full arrows 42, and after engagement along the path indicated by the chain dotted line 43. During engagement the pin 20 will enter the leading portion 36' of groove 36, move along groove 36 into the axial inner end 36'', the path of movement of the pin 20 relatively to the driven member during engagement is indicated in Fig. 9 by the dotted arrows 44.

After the pin 20 has engaged the corresponding groove 36 and reached the closed end 36'' of the groove, thus having accelerated the drive element, projection 48 adjacent the outer end of the pin 21 engages cam surface 55 so that the second pin 21 is pushed into its inner position and into engagement with the inner end 37'' of the corresponding groove 37, whereupon projection 47 adjacent the outer end of the first pin 20 contacts cam surface 56 whereby the first pin 20 is drawn to its outer position and out of engagement with its corresponding groove 36. The clutch is now ready for disengagement and deceleration of the drive element.

The paths of movement of the pins 20, 21 in space and relatively to the driven member 13 before, during and after disengagement are indicated diagrammatically also in Fig. 9. Before disengagement the pins travel along the path indicated by chain dotted line 43, pin 21 being in its inner position in engagement with groove 37 and pin 20 being in its outer or disengageable position, and during disengagement the driving member 16 is moved axially, in the opposite direction to that during engagement, by axial cam 24 and roller 23 so that pin 21 is caused to travel along the path indicated by open arrows, and, after disengagement, along the path indicated by the chain dotted line 41. During disengagement pin 21 travels down groove 37 and leaves the leading portion 37'. The path of movement of pin 21 relatively to the driven member during disengagement is indicated in Fig. 9 by the chain dotted arrows 46. The positions then obtaining immediately after pin 21 leaves groove 37 are indicated diagrammatically in Figs. 7 and 8.

It will be seen that during engagement and disengagement the axial movement of the driving member is related to its movement in the direction of drive and that the phase relationship of the driven member to the driving member is preserved during engagement, when engaged, and during disengagement.

After the deceleration and disengagement has taken place cam surface 53 pushes the first pin 20 into its inner radial position while cam surface 54 draws the second pin 21 into its outer radial position in order to clear the outer face of the driven member when the next engagement of the clutch takes place. Thus the cam surfaces 55 and 56 are used only when the driving member is in the engaged position and the cam surfaces 53 and 54 only when it is disengaged.

The present invention may be readily applied to the clutch which drives the draw mechanism

of a straight bar knitting machine for knitting full fashioned hosiery.

The axial movement of the driving member for the engagement or disengagement of the drive element may be obtained by one or more levers so as to increase the amount of movement obtained from the two axial cams. Moreover, the axial cams may be on the same shaft as the driving member and drive element, or alternatively they may be on another shaft. For example, in a straight bar knitting machine for knitting full fashioned hosiery the invention may as shown in Fig. 10 be applied to the drive of a draw cam 59 on a shaft 11' parallel to the main cam shaft 11 of a machine, the axial cams 22, 24 being on the main cam shaft 11 and the driving member 16 and the driven member 13 being on the parallel shaft, lever 60 pivoted at a point nearer one end than the other interconnecting the axial cams and the driving member 16 and being pivoted at 61 at a point nearer the one end than the other so as to increase the axial movement of the driving member 16 for a given amount of axial movement of the cams 22, 24.

I claim:

1. In a straight bar knitting machine for knitting full fashioned hosiery including at least one intermittently operated element driven in a given direction and means to drive said element, the provision of a clutching device adapted to afford a gradual but positive acceleration of said intermittently operated element in said given direction to bring it into a given phase relationship with said driving means, said clutching device including a driving member and a driven member, one of said members having an abutment of gradually changing direction including a portion directed substantially at right angles to said given direction whilst the other of said members has a withdrawable element adapted to engage said abutment, means being provided for bringing said withdrawable element and said abutment into engagement by producing a condition of relative motion therebetween which motion includes a component in said given direction.

2. In a straight bar knitting machine for knitting full fashioned hosiery including at least one intermittently operated element driven in a given direction and means to drive said element, the provision of a clutching device adapted to afford a gradual but positive acceleration of said intermittently operated element in said given direction to bring it into a given phase relationship with said driving means, said clutching device including a rotating driving member and a rotatable driven member, one of said members having an abutment of gradually changing direction including a portion directed substantially at right angles to said given direction whilst the other of said members has a withdrawable element adapted to engage said abutment and means for bringing said withdrawable element and said abutment into engagement by axial displacement of said driving member during rotation thereof.

3. In a straight bar knitting machine for knitting full fashioned hosiery including at least one intermittently operated element driven in a given direction and means to drive said element, the provision of a clutching device adapted to afford a gradual but positive acceleration of said intermittently operated element in said given direction to bring it into a given phase relationship with said driving means, said clutching device including a driving member and a driven member,

one of said members having an abutment of gradually changing direction including a portion directed substantially at right angles to said given direction whilst the other of said members has a withdrawable element adapted to engage said abutment, means being provided for bringing said withdrawable element and said abutment into engagement by producing a condition of relative motion therebetween which motion includes a component in said given direction, said driven member having a cylindrical outer surface in which said abutment is formed as a curved groove closed at one end and open at the other and said driving member having a pin projecting therefrom for engagement in said groove, the closed end of said groove being directed substantially axially and thus in a direction at right angles to said given direction and the open end thereof being directed at an angle to said given direction corresponding to the direction of relative motion of said driven member and pin at the commencement of interengagement thereof.

4. In a straight bar knitting machine for knitting full fashioned hosiery including at least one intermittently operated element driven in a given direction and means to drive said element, the provision of a clutching device adapted to afford a gradual but positive acceleration of said intermittently operated element in said given direction to bring it into a given phase relationship with said driving means and to afford a gradual but positive retardation of said intermittently operated element to zero in said given direction, said clutch and device including a driving member and a driven member, said driven member having two interconnected abutments each of gradually changing direction and each including a portion directed substantially at right angles to said given direction whilst said driving member has a withdrawable element adapted to engage said abutments, means being provided for bringing said withdrawable element and one of said abutments into engagement by producing a condition of relative motion therebetween which motion includes a component in said given direction, means also being provided for bringing said withdrawable element and the other of said abutments out of engagement by producing another condition of relative motion therebetween which motion includes a component in said given direction, said driven member having a cylindrical hub in the cylindrical surface of which said abutments are formed as curved grooves, each groove having an inner portion and having an outer portion at one end of said hub, said withdrawable element on said driving member comprising a pin projecting therefrom and adapted for engagement with said grooves, the inner portion of each of said grooves extending substantially axially of said hub, and thus in a direction at right angles to said given direction, said inner portion of said two grooves merging into one another to form a single inner portion common to both grooves, the outer portion of one of said grooves extending at an angle to said given direction, said angle corresponding to the direction of relative motion of said driven member and said pin when said pin first comes into contact with said driven member, the outer portion of the other of said grooves extending at another angle to said given direction, said other angle corresponding to the direction of relative motion of said driven member and said pin when said pin comes out of contact with said driven member, whereby to raise the speed of the driven member in said given direction gradually from

zero on interengagement of said pin with said one groove, and to reduce the speed of the driven member in said given direction gradually to zero on disengagement of said pin from said other groove.

5. In a knitting machine according to claim 4, a cam formed on the driving member, and shaped to correspond with the shape of said one of said grooves for moving said pin axially into engagement with the driven member.

6. In a knitting machine according to claim 4, a cam formed on said driving member and shaped to correspond with the shape of said other of said grooves for moving said pin axially out of engagement with the driven member.

7. In a knitting machine according to claim 4, a displaceable member at the junction where said grooves merge into one another, means for resiliently loading said displaceable member to cause it normally to lie across said one of said grooves whilst permitting it to be displaced by said pin to lie across said other of said grooves, whereby to prevent said pin from being withdrawn along said one of said grooves after it has reached said single inner portion common to both grooves and to cause it when withdrawn to move along said other of said grooves.

8. In a straight bar knitting machine for knitting full fashioned hosiery including at least one intermittently operated element driven in a given direction and means to drive said element, the provision of a clutching device adapted to afford a gradual but positive acceleration of said intermittently operated element in said given direction to bring it into a given phase relationship with said driving means and to afford a gradual but positive retardation of said intermittently operated element to zero in said given direction, said clutching device including a driving member and a driven member, said driven member having two abutments each of gradually changing direction and each including a portion directed substantially at right angles to said given direction whilst said driving member has two withdrawable elements each adapted to engage one of said abutments, means being provided for bringing one of said withdrawable elements and one of said abutments into engagement by producing a condition of relative motion therebetween which motion includes a component in said given direction, means also being provided for bringing the other of said withdrawable elements and the other of said abutments out of engagement by producing another condition of relative motion therebetween which motion includes a component in said given direction, said driven member having a cylindrical hub in the cylindrical surface of which said abutments are formed as curved grooves, each groove having an inner portion and having an outer portion at one end of said hub, said withdrawable elements on said driving member comprising pins projecting therefrom, each adapted for engagement with one of said grooves, the inner portion of each of said grooves extending substantially axially of said hub, and thus in a direction at right angles to said given direction, the inner portion of one of said grooves being spaced from the inner portion of the other of said grooves in said given direction by a distance substantially equal to the spacing between said pins projecting from said driving member, the outer portion of one of said grooves extending at an angle to said given direction, said angle corresponding to the direction of relative motion of said driven member and one of said pins when 75

said one of said pins first comes into contact with said driven member, the outer portion of the other of said grooves extending at another angle to said given direction, said other angle corresponding to the direction of relative motion of said driven member and the other of said pins when said other of said pins comes out of contact with said driven member, whereby to raise the speed of the driven member in said given

10 direction gradually from zero on interengagement of said one pin with said one groove, and to reduce the speed of the driven member in said given direction gradually to zero on disengagement of said other pin from said other groove.

15 9. In a knitting machine according to claim 8, a cam formed on the driving member and shaped to correspond with the shape of said one of said grooves for moving said one of said pins axially into engagement with the driven member.

20 10. In a knitting machine according to claim 8, a cam formed on the driving member and shaped to correspond with the shape of said other of said grooves for moving said other of said pins axially out of engagement with said driven member.

25 11. In a knitting machine according to claim 8, means for radially moving said spaced pins individually to render them respectively operative and inoperative and means for collectively moving said spaced pins axially whereby during engagement of said clutch said one of said pins is caused to move along said one of said grooves and during disengagement of said clutch said other of said pins is caused to move along said other of said grooves.

30 35 12. In a knitting machine according to claim 11 cams disposed in the paths of said pins and co-operating with axial projections on the pins to effect radial movement thereof.

40 13. In a knitting machine according to claim 12 two sets of cams disposed in spaced relationship in the axial direction of the driving member so that one is set in the path of the pins when in the disengaged position and the other is set in the path of the pins in the engaged position.

45 14. In a straight bar knitting machine for knitting full fashioned hosiery including at least one intermittently operated cam driven in a given direction and means to drive said cam, the provision of a clutching device adapted to afford a gradual but positive acceleration to said intermittently operated cam in said given direction to bring it into a given phase relationship with said driving means, said clutching device including a driving member and a driven member, said driven member having an abutment gradually changing in direction and including a portion directed substantially at right angles to said given direction whilst said driving member has a withdrawable element adapted to engage said abutment, means being provided for bringing said withdrawable element and said abutment into engagement by producing a condition of relative motion therebetween which motion includes a component in said given direction.
